UNITED STATES PATENT OFFICE.

CHARLES CHEERS WAKEFIELD, OF LONDON, ENGLAND.

FORCE-FEED LUBRICATOR.

1,134,566.

Specification of Letters Patent.

Patented Apr. 6, 1915.

Application filed May 13, 1914. Serial No. 838,274.

To all whom it may concern:

Be it known that I, CHARLES CHEERS WAKEFIELD, a subject of the King of England, residing at London, England, have 5 invented certain new and useful Improvements in Force-Feed Lubricators, of which the following is a specification.

This invention is for improvements in or relating to force-feed lubricators of the type 10 having a plurality of pumps operated through a driving-member common to them all, by an eccentric and each having a separately adjustable device whereby its effective stroke may be adjusted so that its delivery 15 may be controlled independently of the other pumps.

According to the present invention, there is provided in a force feed lubricator of the type described, a driving-member having 20 a stem sliding in a hollow vertical guide, a plurality of plunger pumps disposed on opposite sides of the stem, a head on the driving-member having a flange which extends laterally to operate as a tappet-plate 25 for the pumps, tappet-members adjustably mounted in the head for operating the pump-plungers and an opening in the head to receive an eccentric whereby the driving-member is driven.

30 The invention further relates to a force-feed lubricator having a plurality of pumps, a separately adjustable member for each pump, and a single device for adjusting simultaneously the adjustable members of 35 all the pumps without disturbing the original adjustment of each to the other, so that where the proportion of lubricant to be delivered to each part has been once decided, the delivery may be increased 40 throughout the whole system while still maintaining the same relative proportions of the delivery to the different parts.

In the accompanying drawings which 45 illustrate one method of carrying out this invention:—Figure 1 is a central vertical section through the lubricator; Fig. 2 is a central vertical section through the casing of the lubricator at right angles to the section shown in Fig. 1, with the interior members in full; Fig. 3 is a plan of the lubricator with one half in section on the line 3—3 of Fig. 1; Fig. 4 is a section through the operating-member of the pumps on the line 4—4 of Fig. 1, Fig. 5 is a plan view 50 of a controller for use with the lubricator;

Fig. 6 is a plan view of a controller and lubricator.

Same letters indicate the same parts throughout the drawings.

The working parts of the lubricator are 60 mounted in a container A which also serves as a reservoir for the lubricant.

The driving-member of the lubricator comprises a head B having in it a slot B¹ which receives the operating cam C¹ of a 65 cam-shaft C mounted in bearings C² in the casing A. The head B has a hollow stem B² which has a sliding fit in a socket A¹ formed integral with the casing A and constituting a hollow vertical guide for the 70 driving-member. The socket is closed at the bottom where it has a screw-threaded extension A² whereby the whole apparatus may be secured to any convenient support.

Grouped around the driving-member B 75 is a series of pumps which are of known construction, and in themselves form no part of the present invention. Each pump comprises a barrel D rigidly supported in the bottom of the casing A and sliding in 80 the barrel is a plunger D¹. The barrel is provided with lubricant inlet ports D² which are uncovered by the plunger when in the raised position shown in Fig. 1, so that lubricant can enter from the casing A, 85 which lubricant is afterward discharged past a valve E and into a delivery conduit E¹ when the plunger descends. To further secure the covering of the ports D² the plunger carries an outer sleeve D³ which 90 slides over the barrel and moves up and down with the plunger. This sleeve is shouldered at D⁴ and is received in a jaw B³ formed in a flange B⁴ on the head B of the driving-member. The flange B⁴ is provided with a series of jaws, one for each 95 pump-plunger, so all the plungers can be raised simultaneously by the upward movement of the driving-member through the engagement of the flange with the aforesaid shoulder D⁴ on each plunger sleeve.

The head B has a second flange B⁵ above and parallel to the flange B⁴, and in this is mounted a series of adjustable tappets F. Each tappet is screwed into the flange and 105 one end engages the top of the pump-plunger as the tappet descends and at the other end carries a pinion F¹. The pinions are grouped around and all mesh with a central gear-wheel F² carried by a shaft G which is 110

mounted in a bearing in the top cover A³ of the casing. The spindle projects through the cover and above the cover carries a double grooved pulley G¹. In each groove, 5 an operating cord or flexible wire G² is secured, and these wires extend out between rollers G³ on the cover to an operating-member shown in Fig. 5. The wires are led into a hollow stem H carrying an arm H¹. The stem H is mounted in a lug H² on a bracket H³ secured in any convenient position near the driver or other operator. The stem H is screw-threaded and clamped in position by nuts H⁴ which grip the lug H² 10 on opposite sides. The double cord G² is carried around an operating wheel J pivoted at J¹ to the arm H¹ and the cords are fixed to the operating wheel at J² so that when the wheel is moved the cords must be 15 positively moved with it. The wheel has a control-handle J³ and stops J⁴ which co-operate with the arm H¹. In the periphery of the wheel or a disk thereon notches J⁵ are provided which co-operate with any convenient form of spring-controlled detent, indicated at J⁶.

It will be seen that the end of the spindle G is stepped into a cup-bearing G⁴ which is screw threaded into the head B of the operating-member. This cup-bearing serves a double purpose, as when it is out of the head, it enables the opposed projecting portion b to be machined so that it may provide a good bearing surface for the eccentric C¹, and the under-side of the bearing-cup G⁴ can also be itself machined to constitute the opposite bearing-face for the eccentric C¹, moreover, this cup-bearing G⁴ can easily be sunk further into the head to 30 take up wear.

The operation of this apparatus is as follows:—Before mounting the wheel F² in place, it will be seen that each of the tappets F can be adjusted so that the pump it 35 controls shall deliver the proper proportion of lubricant to the part it is intended to feed. Thus the tappet on the left of Fig. 1 is shown closer up to its plunger than that on the right-hand side so that the left hand 40 pump will give a fuller delivery than the right-hand pump at each stroke. The requisite adjustment having been ascertained, the wheel F² is now dropped into position and when connected up by the operating wires 45 to the operating handle J³ all the tappets will be held against rotation so that they 50 will remain at the adjustment at which they have been set. As the eccentric shaft C rotates the eccentric will constantly reciprocate the operating head B so that the flange B⁴ first lifts all the pumps to draw lubricant 55 into the pump barrels and then the tappets F thrust the plungers down to discharge the lubricant into their respective conduits. If 60 now the driver comes to a bank or has a 65

particularly heavy load on his engine so that he desires to increase the feed of lubricant throughout the system he swings the handle J³ over in the direction of the arrow, Fig. 5. This movement will cause the wheel F² to be rotated in a counter-clockwise direction as viewed in Fig. 3, so that all the pinions F¹ will be rotated in a clockwise direction and the tappets will thus be screwed farther into the flange B⁵ of the head B and a greater proportion of the stroke of each pump-plunger will thus be rendered effective. It will be observed that this increase of the effective operation of the pump-plungers increases the total delivery throughout the system but without varying the proportion of the delivery of one pump relatively to another. Similarly, if the driver requires to decrease the general delivery of lubricant throughout the system the control handle J³ can be moved in the reverse direction, that is, to the right of Fig. 5, whereupon all the tappets will be drawn farther away from their respective pump plungers.

In a casing A a strainer A⁴ is conveniently mounted, so that when filling the container, lubricant can be poured through this, and a conduit A⁵ may be formed in one or more of the walls of the container to receive connections A⁶, A⁷ whereby steam may be passed through the wall of the chamber to heat the lubricant.

It has before been proposed in lubricators to employ a hollow vertical guide in which reciprocates a stem and head operated by an eccentric and having an upper flange carrying an adjustable tappet for effecting the down-stroke of a single pump-plunger, and a lower flange for effecting the up-stroke of the same. Further, it is not in itself new to form the stem of the operating member integral with the head and the hollow guide integral with the oil-container. It will be appreciated that these features are only details of construction for which no claim is made *per se* in the present application.

What I claim as my invention and desire to secure by Letters Patent is:—

1. In a force-feed lubricator the combination of, a plurality of delivery pumps, a separately adjustable member for controlling the delivery of each pump, and a single device for adjusting simultaneously the said adjustable members of all the pumps, substantially as set forth.

2. In a force-feed lubricator the combination of, a plurality of delivery pumps, a separately adjustable member for controlling the delivery of each pump, a single device for adjusting simultaneously the said adjustable members of all the pumps, an actuating-member situated at a distance from the lubricator, and means operatively connecting the said actuating-member with the

single adjusting-device aforesaid, for the purpose set forth.

3. In a force-feed lubricator the combination of, a plurality of plunger-pumps, driving-means for moving the pump-plungers in one direction such means providing for lost-motion between it and the plungers, means for returning the plungers, said driving means including a screw-threaded stud 10 for each pump-plunger operatively connected therewith in such manner as to take up more or less of the lost-motion as the stud is screwed further into or out from its support, and a single device which engages all 15 of these studs in such manner that when moved it rotates them all simultaneously, for the purpose set forth.

4. A force-feed lubricator, comprising a plurality of plunger pumps, means including a tappet carrying plate and tappets carried thereby for moving the plungers in one direction, means for adjusting said tappets relative to the plate and to each other, means for moving the plungers in the other direction, and an actuating device engaging all 25 of the tappets to simultaneously adjust all of the tappets relative to the plate, for the purpose set forth.

5. A force-feed lubricator, comprising a plurality of plunger pumps, means including screw threaded studs for moving the pump plungers in one direction, a pinion on each stud, a single toothed wheel engaging all of the pinions of the studs to simultaneously 35 rotate all of the studs, and means for moving the plungers in the other direction; substantially as described.

6. In a force-feed lubricator the combination of, a plurality of plunger-pumps having their plungers parallel one to another, a driving-member comprising a stem sliding in a tubular guide parallel to the plungers of the pumps being grouped about the longitudinal axis of said stem and guide, the 40 driving-member having a head provided with a flange (B⁵) which extends laterally into the path of the pump-plungers to operate as a tappet-plate for moving them in one direction, means for returning the plungers, screw-threaded tappet studs (F) 45 mounted on each pump-plunger and each adjustable to and from the plunger by rotating it, and a driving-shaft for the stem having an eccentric which lies in an opening (B¹) in the head of the stem, substantially as set forth.

7. In a force-feed lubricator the combination of, a plurality of plunger-pumps having their plungers parallel one to another, a driving member comprising a stem sliding 50 in a tubular guide parallel to the plungers of the pumps, the pumps being grouped about the said stem, the driving-member having a head provided with a flange (B⁵) which extends laterally into the path of the pump-plungers to operate as a tappet-plate 55 for moving them in one direction, means for returning the plungers, screw-threaded tappet studs (F) one for each pump-plunger mounted on the flange and adjustable in the direction of movement of the parts, pinions, one on each screw-threaded tappet-stud, a gear-wheel engaging all of these pinions, means for operating this gear-wheel so that

for moving them in one direction, means for returning the plungers, screw-threaded tappet-studs (F) one for each pump-plunger mounted on said flange, and arranged to be adjustable in the direction of movement of the parts, and a driving-shaft for the stem having an eccentric which lies in an opening (B¹) in the head of the stem, substantially as set forth.

8. In a force-feed lubricator the combination of, a plurality of plunger-pumps having their plungers parallel one to another, a driving-member comprising a stem sliding in a tubular guide parallel to the plungers of the pumps, the pumps being grouped about the longitudinal axis of said stem and guide, the driving-member having a head provided with two flanges (B⁴, B⁵) separated one from the other and operatively engaging a part of the pump-plungers between them so that they serve as tappet-plates to move the pump-plungers backward and forward, tappet-members one for each pump-plunger mounted on the flange and adjustable in the direction of movement of the parts, and a driving-shaft for the stem having an eccentric which lies in an opening (B¹) in the head of the stem, substantially as set forth.

9. In a force-feed lubricator the combination of, a plurality of plunger-pumps having their plungers parallel one to another, a driving-member comprising a stem sliding in a tubular guide parallel to the plungers of the pumps the pumps being grouped about the said stem, the driving-member having a head provided with a flange (B⁵) which extends laterally into the path of the pump-plungers to operate as a tappet-plate for moving them in one direction, means for returning the plungers, screw-threaded tappet studs (F) 100 screwed into the flange one for each pump-plunger and each adjustable to and from the plunger by rotating it, and a driving-shaft for the stem having an eccentric which lies in an opening (B¹) in the head of the stem, substantially as set forth.

10. In a force-feed lubricator the combination of, a plurality of plunger-pumps having their plungers parallel one to another, a driving-member comprising a stem sliding in a tubular guide parallel to the plungers of the pumps, the pumps being grouped about the said stem, the driving-member having a head provided with a flange (B⁵) 115 which extends laterally into the path of the pump-plungers to operate as a tappet-plate for moving them in one direction, means for returning the plungers, screw-threaded tappet studs (F) 120 one for each pump-plunger mounted on the flange and adjustable in the direction of movement of the parts, pinions, one on each screw-threaded tappet-stud, a gear-wheel engaging all of these pinions, means for operating this gear-wheel so that

when it is turned all the pinions and consequently the studs turn with it, and a driving-shaft for the stem having an eccentric which lies in an opening (B¹) in the head of the stem, substantially as set forth.

11. In a force-feed lubricator the combination of, a plurality of plunger-pumps having their plungers parallel one to another, a driving-member comprising a stem 10 sliding in a tubular guide parallel to the plungers of the pumps, the pumps being grouped about the said stem, the driving-member having a head provided with a flange (B⁵) which extends laterally into the 15 path of the pump-plungers to operate as a tappet-plate for moving them in one direction, means for returning the plungers, screw-threaded tappet-studs (F), screwed into the flange one for each pump-plunger 20 and each adjustable to and from the plunger by rotating it, pinions one on each screw-threaded tappet-stud, a gear-wheel engaging all of these pinions, means for operating this gear-wheel so that when it is turned all 25 the pinions and consequently the studs turn with it, and a driving-shaft for the stem having an eccentric which lies in an opening (B¹) in the head of the stem, substantially as set forth.

12. In a force-feed lubricator the combination of, a plurality of plunger-pumps having their plungers parallel to one another, an oil reservoir within which all the plunger-pumps are mounted, a driving-member mounted within the oil reservoir and comprising a stem sliding in a tubular guide made integral with and depending from the bottom of the oil reservoir and parallel to the plungers of the pumps, the 35 pumps being grouped about the longitudinal axis of said stem and guide, the driving-member having a head integral with the stem and provided with a flange which extends laterally into the path of the pump-plungers to operate as a tappet-plate for 40 moving them in one direction, means for returning the plungers, tappet-members one for each pump-plunger mounted on the flange and adjustable in the direction of 45 movement of the parts, and a driving-shaft for the stem having an eccentric which lies 50

in an opening (B¹) in the head of the stem, substantially as set forth.

13. In a force-feed lubricator the combination of, a plurality of plunger-pumps having their plungers parallel one to another, a driving-member comprising a stem 55 sliding in a tubular guide parallel to the plungers of the pumps, the pumps being grouped about the longitudinal axis of said stem and guide, the driving-member moreover having a head made integral with it and provided with a flange (B³) which extends laterally into the path of the pump-plungers to operate as a tappet-plate for 60 moving them in one direction, the said head moreover having a throughway (B¹) in it to receive an eccentric for driving the same, a screw-threaded plug (G⁴) inserted in the head from one side and projecting into the 65 throughway (B¹) to form a bearing-face for the eccentric and enable the opposed face to be machined, means for returning the plungers, and tappet-members one for each 70 pump-plunger mounted on the flange and 75 adjustable in the direction of movement of the parts, substantially as set forth.

14. A force feed lubricator, comprising a plurality of pumps, means for simultaneously operating all of said pumps, independent means for controlling the feed to each pump, and an actuating device for simultaneously adjusting all of the feed controlling devices; substantially as described.

15. A force feed lubricator, comprising a plurality of pumps, means for simultaneously actuating all of said pumps, an independent adjustable device for controlling the effective stroke of each pump, and a single device for simultaneously adjusting all 85 of the independent adjustable devices to simultaneously vary the effective stroke of 90 each of the pumps; substantially as described.

In testimony whereof I have signed my 95 name to this specification in the presence of two subscribing witnesses.

CHARLES CHEERS WAKEFIELD.
